UNITED STATES PATENT OFFICE.

ARTHUR MIDDLETON ROSE, OF YONKERS, NEW YORK, ASSIGNOR TO THE
WORCESTER CARPET COMPANY, OF MASSACHUSETTS.

DESIGN FOR A CARPET-BODY.

SPECIFICATION forming part of Design No. 23,821, dated November 27, 1894.

Original application filed August 22, 1894, Serial No. 521,035. Divided and this application filed October 12, 1894. Serial No. 525,730. Term of patent 33 $\frac{1}{2}$ years.

To all whom it may concern:

Be it known that I, ARTHUR MIDDLETON ROSE, residing at Yonkers, county of Westchester, State of New York, have invented and produced a new and original Design for a Pattern to be Wrought in the Body of Brussels and Wilton Carpets in such Colors as May be Desired, of which the following is a specification.

- 5 This application is a division of application, Serial No. 521,035, filed by me August 22, 1894, wherein the body is claimed in combination with a suitable border therein shown. The design of the body consists of eight 10 lozenge-shaped panels similar in outline and size, and all having ornamentation of figures and of a lace work character, the ornamentation of each panel being different in details. The panels are separated from each other by 15 wavy lines, with ornamental figures at the points where any two wavy lines approach each other. Two of the panels are arranged in lines along the middle of a carpet breadth, with their ends connecting, and four are arranged in two lines, one along one side and the other along the other side of the carpet 20 breadth. These latter four panels are placed side by side and end to end, and their adjoining sides and ends form one of the middle 25 breadth panels. The other two panels are 30

shown, each in two half sections, along the edges of the carpet breadth, with their ends connecting. One half of each section lies along one side of the middle panels and the other half of this section lies along the other 35 side of the next middle panel. This arrangement results when the carpet is put together, in longitudinal and transverse rows of connected panels. There are four longitudinal rows, in each of which the panels are different from those in the other rows, and in each of which there are two patterns of panels which alternate. There are two transverse rows, in each of which the panels are four in number, each panel being repeated every 40 fourth one. One of these rows is made up of the panels arranged on either side of the middle of the breadth, and the other of these rows is made up of the panels arranged along the middle and along the edges of the breadth. 45 50

What I claim, and desire to secure by Letters Patent, is—

The design for a carpet body, substantially as shown.

Signed by me, in New York city, this 5th 55 day of October, 1894.

ARTHUR MIDDLETON ROSE.

In presence of—

N. A. McMANUS,
SCIPION PRUJOL.
